UNITED STATES PATENT OFFICE.

S. MASON MEEK, OF CHICAGO, ILLINOIS.

FILE FOR HOLDING BLANKS.

SPECIFICATION forming part of Letters Patent No. 314,598, dated March 31, 1885.

Application filed April 11, 1883. (No model.)

To all whom it may concern:

Be it known that I, S. MASON MEEK, a citizen of the United States, residing at Chicago, in the county of Cook and State of Illinois, 5 have invented a certain new and useful Improvement in Files for Holding Legal or other Blanks and Stationery, of which the following is a specification.

My invention relates to improvements in cases for the reception of legal and other blanks and stationery, and the object thereof is, first, to provide a blank-case taking up the smallest possible room, and capable of being adjusted so as to hold many or few blanks, and leave 15 no compartment or space open or exposed to dust, whether full or empty; to make the blank-case light and portable, yet capable of holding a large variety of different kinds of blanks or stationery, so arranged and indexed 20 that the different varieties may be easily distinguished. I attain this end by making all the parts adjustable and so arranged on cords, with bellows-work on the sides of the compartments, that the weight of the contents will 25 close up and keep closed the bottom of the compartments when the case is hung on a wall, as it is intended to be when in use, the blanks resting on the lacing through or at the bottom of the compartments. The capacity 30 for receiving blanks is increased or diminished by slackening or tightening the cords at the top and bottom of said case, intending that the lacing of the lower cord be tighter than the upper, so that the blanks will, when in the 35 case, cause the front to sag down far enough to close up the bottom of the compartments and cause the compartments to stand open at the top, thus holding the blanks securely in place and preventing dust from rising between 40 them from the bottom, thus avoiding the necessity of bellows-work at the bottom of the compartments.

The mode of construction and using my invention will be understood by the following 45 explanation of accompanying drawings, in which—

Figure 1 is a front view of the blank-case when closed and partially filled. Fig. 2 is a perspective view of the blank-case, showing 50 the bellows-work, the cords which support the same slackened, so as to show their use and how they are put in place. Fig. 3 is a side

view. Fig. 4 is a back view showing cords and how adjusted.

Similar letters refer to similar parts throughout the several views. 55

a a and *b* represent flexible flaps and cover. *d* represents an elastic cord or spring looped to an eyelet-hook on the front *e* of the blank-case and passed over similar hooks or buttons 60 on the flaps *a a* and cover *b*, thus drawing the flexible cover and flaps snugly down over the heads of the blanks in the compartments, and at the same time drawing the upper end 65 of the compartments close upon the contents of the case, so as to keep the contents of the case straight and to exclude dust.

C represents bellows-work at the ends of the compartments, and allowing them to open and close at will. 70

i represents a series of partitions which form compartments, which are suspended or strung on the cord *g* by means of the eyelets *f*, being graded in length from the length of the back *k* to that of the front *e*, and being intended 75 to be made in the proportion of one to two, thus allowing the weight in the compartments to be suspended by the cord fastened to the back of the case, thus letting the cord hang as near vertical as possible to give strength to the 80 structure.

ff represent a series of eyelets, both above and below and in the four corners of each partition, forming the compartment, through 85 which pass strong cords and also fasten compartments securely in place.

g at the top of the case represents strong cords passing through the eyelets *f* from the back, thence down through the upper corners of the compartments on one side, then out 90 through the front of the case *e*, lacing out and in across the front, thence passing through the corners from the outside of the front *e* and up through the eyelets *f* in the opposite corners of said compartments through the back, 95 to tie to the other end of said cord.

g' at the bottom represents a strong cord which is passed through eyelets in the back and also through eyelets in the bellows-work *c* in the lower corner of each compartment; 100 thence it laces through or beneath the compartments, lacing backward and forward through the back and front, as seen by reference to accompanying drawings, the lower

cord being intended to be drawn up closer than the cord at the top, which is necessarily longer than the lower cord, the cords to be so adjusted to each other that when the compartments are full or partially filled the downward pressure on the cords will cause the bottom to close up on the contents, and at the same time allow the upper part of the compartments to lean out from the wall or back of the case. I prefer to make this case about twenty-six (26) inches long by thirteen (13) inches wide. The front and back I prefer to make of wood or stiff pasteboard, bound with tin or brass to strengthen it, the sides of the compartments of cloth, paper, or leather, and the partitions and cover or flaps of paper, leather, oil-cloth, or either or all of them, the flaps to be indexed on the inside to correspond with letters or figures on each compartment.

The eyelets are used for the double purpose of securing the corners and to allow the compartments to spread easily by sliding on the

cord, so as to adjust themselves to the position of the cord, whether the case is full or empty. I do not, however, limit myself to all or any of the above materials or dimensions, desiring to make them of the dimensions and materials best suited to meet the wants of the consumers.

What I desire to claim and secure by Letters Patent is—

A file for holding blanks, consisting of a case having the front *e* and back *k* with partitions *i i* between them and secured thereto by cords *g g* through eyelets *f f* in each of the parts, and the flaps *a a* and covers *b*, secured to the back and adapted to be infolded over the front to close the case and to be secured together and to the front by an elastic cord or spring, *d*, over eyelet-hooks, as shown and described.

S. MASON MEEK.
